UNITED STATES PATENT OFFICE.

JAMES E. McCULLOCH, OF KENSINGTON, MARYLAND.

EYESHADE.

Application filed July 16, 1927. Serial No. 206,263.

The present invention relates to eye shades, and aims to provide a simple and practical eye shade which may be inexpensively manufactured.

5 Another object is the provision of such a device which may be readily made from a few simple parts, and which may be used as an advertising novelty having practical utility.

10 With the foregoing and other objects in view, which will be apparent as the description proceeds, the invention resides in the construction and arrangement of parts, as hereinafter described and claimed, it being understood that changes can be made within the scope of what is claimed, without departing from the spirit of the invention.

15 The invention is illustrated in the accompanying drawing, wherein—

20 Figure 1 is a top plan view of the improved eye shade in the position it assumes when worn.

Fig. 2 is a side elevation thereof.

25 Fig. 3 is a rear view, portions being broken away.

Fig. 4 is a top plan view illustrating a modification.

30 In carrying out the invention there is provided a transverse yoke 7 formed from a length of suitable resilient wire, which is twisted intermediate its ends to provide the depending shank 8 having the curved nose piece 9 to seat on the nose for supporting the eye shade in place. The yoke 7 and 35 nose piece may also be made of other suitable flexible or resilient material.

35 Temples 10, also formed from suitable resilient wire, are hingedly connected with the ends of the yoke 7, the adjacent ends of 40 said yoke and temples having the overlapping eyes 11 through which rivets or other pivot elements 12 are engaged. The temples 10 have hooks 13 to engage behind the ears, and the yoke 7 is normally straight when 45 removed from the head, but when the eye shade is applied with the intermediate portion of the yoke 7 bearing against the forehead and the hooks 13 engaged behind the ears the yoke 7 is sprung rearwardly at its 50 ends so as to assume a slightly curved shape, as seen in Fig. 1. An elastic or cord 11^a is also shown connected to the ends of the yoke 7 and may be passed behind the head to assist in holding the yoke in place on the 55 forehead, and it is possible to use either the

temples 10 or the elastic 11^a without the other.

A vizor or shade piece 14, formed from a sheet of celluloid or other suitable resilient material, is hingedly mounted on the yoke 7. 60 Thus, the upper or rear edge portion of the vizor 14 is bent back and riveted or otherwise secured to provide the elongated loops 15 loosely embracing the yoke 7 between the shank 8 and ends of the yoke, to permit 65 the vizor or shade piece to be turned on said yoke. The hinged edge portion of the vizor is cut away, as at 16, between the portions 15, to permit the vizor to swing to a downwardly and forwardly extending position, 70 as seen in Fig. 2, and the edge of the cut away portion 16 contacting with the shank 8 will limit the downward movement of the vizor so as to support it at the desired angle in front of the eyes. 75

Although the vizor or shade piece 14 is normally flat, it is sprung into curved shape with the yoke 7 when the eye shade is applied, and this creates a tendency for the vizor to swing downwardly and bear against 80 the shank 8. The vizor may be swung upwardly to the dotted line position as seen in Fig. 2, and in swinging past a horizontal position will spring either upwardly or downwardly due to the flexing of the vizor 85 with the yoke 7. The vizor thus has a snapping action when swung upwardly and downwardly, with the device applied.

When the shade is removed, the vizor 14 and yoke 7 straighten out, and by swinging 90 the vizor 14 upwardly and rearwardly behind the shank 8 and nose piece 9, the temples 10 may be swung together behind the vizor, with the device in compact folded position so that it may be carried in the 95 pocket or stored away within small space, or if the elastic 10^a is used without the temples 10 the device is even more readily stored away or pocketed.

Fig. 4 illustrates temples 10' which are 100 adapted to bear under slight spring pressure against the temples of the head, instead of hooking behind the ears, and the eyes 11 of the temples 10' have stops 17 to contact with the yoke 7 and limit the outward swinging 105 movement of the temples 10' so that said temples are sprung outwardly, as seen in Fig. 4, when applying the temples to the head, and the yoke 7 is also sprung forwardly 110 at its ends so as to be curved reversely to the

curvature as seen in Fig. 1. Thus, when the temples 10' are swung outwardly the stops 17 contacting with the yoke 7 will limit the swinging movement of the temples 10' and further separation thereof will spring the yoke 7 and temples so that the temples will bear under pressure against the head. The vizor or shade 14 is also sprung so as to have the snapping or flipping action in swinging upwardly and downwardly.

The vizor or shade piece 14 may be made of different materials and may be of different colors. The vizor may also be used for advertising purposes, so that the device will provide an inexpensive and practical novelty.

Having thus described the invention, what is claimed as new is:—

- 20 1. An eye shade comprising a normally straight resilient yoke, a normally flat flexi-

ble vizor having one edge portion mounted for turning movement on said yoke, and retaining means connected to the terminals of the yoke and applicable to the head of the wearer in a manner to spring the yoke into curved shape, so as to similarly spring said vizor. 25

2. An eye shade comprising a normally straight flexible yoke having a nose piece between its ends, a vizor composed of a piece of flat flexible material bent back along one edge and loosely embracing said yoke for turning movement, and retaining means connected to the terminals of the yoke and applicable to the head of the wearer in a manner to spring said yoke into curved shape, so as to similarly spring the vizor. 30 35

In testimony whereof I hereunto affix my signature.

JAMES E. McCULLOCH.
